UNITED STATES PATENT OFFICE.

ROSCOE ROYAL, OF CHICAGO, ILLINOIS, ASSIGNOR TO CORWIN TELEPHONE MANUFACTURING COMPANY, OF CHICAGO, ILLINOIS, A CORPORATION OF ILLINOIS.

TELEPHONE-TRANSMITTER.

1,040,637.

Specification of Letters Patent. Patented Oct. 8, 1912.

Application filed August 11, 1911. Serial No. 843,598.

To all whom it may concern:

Be it known that I, ROSCOE ROYAL, citizen of the United States, residing at Chicago, in the county of Cook and State of Illinois, have invented a certain new and useful Improvement in Telephone-Transmitters, of which the following is a full, clear, concise, and exact description, reference being had to the accompanying drawings, forming a part of this specification.

My invention relates to transmitters of the type commonly known as the granular carbon type and has for its object the provision of means whereby vibrations at the centers of the speaking diaphragms are not directly communicated to movable electrodes but are permitted to decrease in amplitude without causing corresponding fluctuation in transmitted telephonic currents so that the frequency of such transmitted currents is reduced whereby such currents are adapted to be transmitted over longer distances, the transmitter of my invention thus being of particular service for long distance telephony.

My invention may generally be described as comprising a transmitter including a stationary cup having a flexible closure, transmitter electrodes presented to the interior of the cup, one of these electrodes being carried by the flexible closure so as to be movable, comminuted current conducting material within the cup and interposed between the electrodes for electrically connecting the same in the transmitter circuit, a speaking diaphragm and a medium for conducting vibrations interposed between the electrode carried by the flexible closure and a portion of the speaking diaphragm laterally disposed with respect to said electrode. In the preferred embodiment of my invention I employ a spring structure mechanically constituting a continuation of said medium and serving to press said medium into engagement with the diaphragm.

I will explain my invention more fully by reference to the accompanying drawing showing the preferred embodiment thereof and in which like parts are indicated by similar characters of reference throughout the different figures.

A mouth piece *a* is screwed within a mounting plate *b* for the various parts of the transmitter, which mounting plate may also support a housing, not shown, for trans-

mitter parts located to the rear of said mounting plate. A bridge *c* is secured to a flange *d* projecting rearwardly from the mounting plate *b*. A cup *e* is provided with a rearwardly extending stem *f* that passes 60 through an aperture in the bridge and which is secured in position by means of a clamping screw *g* so that the cup is normally stationary, though adjustable in position. The cup is provided with a flexible 65 closure *h*, preferably made in the form of a disk of mica. This closure is secured in position upon the cup by means of the flange clamping ring *i*. The flexible closure *h* carries a button that has a facing of carbon 70 *k*, preferably in the form of a carbon disk. The base of the cup is provided with a facing of carbon *l* preferably also in the form of a carbon disk. The elements *k* and *l* constitute electrodes of the transmitter and 75 are preferably included in circuit by means of the conductors *m* and *n*, independently of the speaking diaphragm that is later referred to. Comminuted conducting material, preferably in the form of carbon, is 80 located within the cup so as to be in contact with the electrodes *k* and *l*, this granular element being indicated at *o*. As the function of the element *o* is well understood I will not describe the same. A speaking 85 diaphragm *p* is held, at its periphery, against the rear of the mounting plate *b* by means of a spring structure that is preferably formed in two symmetrically related bent strip springs *q*, these springs exerting 90 pressure upon the speaking diaphragm through the intermediation of buttons or prongs *r* of insulating material, under the assumption that the speaking diaphragm is not to be included in circuit. These buttons or prongs *r* engage portions of the speaking diaphragm *p* that are laterally displaced 95 with respect to the movable electrode *k* that is carried by the cup closure *h*. A medium for transferring vibrations from the speaking 100 diaphragm to the movable electrode *k* desirably resides in a substantially rigid yoke *s* that is preferably integrally formed with the springs *q*. This yoke is attached 105 at its center to the button that is in fixed relation with the electrode *k*, current finding passage by way of the elements *s* and *q* to the conductor *n*. The vibrations imparted to the speaking diaphragm by a speaker's voice have greatest amplitude 110

at the center of the diaphragm, that point which is in axial alinement with the transmitter electrode. The buttons *r* engage the speaking diaphragm laterally of the electrode *k* so that this electrode does not move in accordance with the greatest amplitudes of vibrations of the speaking diaphragm but does move in accordance with vibrations of the speaking diaphragm where such vibrations are less prominent and are of lower frequency with the advantages that have hitherto been pointed out.

Having thus described my invention I claim as new and desire to secure by Letters Patent the following:

1. A telephone transmitter including a stationary cup having a flexible closure; transmitter electrodes presented to the interior of the cup, one of these electrodes being carried by the flexible closure so as to be movable; comminuted current conducting material within the cup and interposed between the electrodes for electrically connecting the same in the transmitter circuit; a speaking diaphragm; and a medium for conducting vibrations interposed between the electrode carried by the flexible closure and a portion of the speaking diaphragm laterally disposed with respect to said electrode; such interposition of said medium between the electrode carried by the flexible closure and the speaking diaphragm being independent of the aforesaid stationary cup; and a spring structure for pressing said medium into engagement with the speaking diaphragm where it engages the same.
2. A telephone transmitter including a stationary cup having a flexible closure; transmitter electrodes presented to the interior of the cup, one of these electrodes being carried by the flexible closure so as to be movable; comminuted current conducting material within the cup and interposed between the electrodes for electrically connecting the same in the transmitter circuit; a speaking diaphragm; and a medium for conducting vibrations interposed between the electrode carried by the flexible closure and a portion of the speaking diaphragm laterally disposed with respect to said electrode, such interposition of said medium between the electrode carried by the flexible closure and the speaking diaphragm being independent of the aforesaid stationary cup; and a spring structure for pressing said medium into engagement with the speaking diaphragm where it engages the same.

3. A telephone transmitter including a stationary cup having a flexible closure; transmitter electrodes presented to the interior of the cup, one of these electrodes being carried by the flexible closure so as to be movable; comminuted current conducting material within the cup and interposed between the electrodes for electrically connecting the same in the transmitter circuit; a speaking diaphragm; and a medium for conducting vibrations interposed between the electrode carried by the flexible closure and the speaking diaphragm laterally disposed with respect to said electrode, such interposition of said medium between the electrode carried by the flexible closure and the speaking diaphragm being independent of the aforesaid stationary cup; and a spring structure for pressing said medium into engagement with the speaking diaphragm where it engages the same.
4. A telephone transmitter including a stationary cup having a flexible closure; transmitter electrodes presented to the interior of the cup, one of these electrodes being carried by the flexible closure so as to be movable; comminuted current conducting material within the cup and interposed between the electrodes for electrically connecting the same in the transmitter circuit; a speaking diaphragm; and a medium for conducting vibrations interposed between the electrode carried by the flexible closure and the speaking diaphragm laterally disposed with respect to said electrode, such interposition of said medium between the electrode carried by the flexible closure and the speaking diaphragm being independent of the aforesaid stationary cup; and a spring structure for pressing said medium into engagement with the speaking diaphragm where it engages the same.

5. A telephone transmitter including a stationary cup; and a spring structure mechanically constituting a continuation of said medium and serving to press said medium into engagement with the diaphragm.

6. A telephone transmitter including a stationary cup having a flexible closure; transmitter electrodes presented to the interior of the cup, one of these electrodes being carried by the flexible closure so as to be movable; comminuted current conducting material within the cup and interposed between the electrodes for electrically connecting the same in the transmitter circuit; a speaking diaphragm; and a substantially rigid medium for conducting vibrations interposed between the electrode carried by the flexible closure and a portion of the speaking diaphragm laterally disposed with respect to said electrode, such interposition of said medium between the electrode carried by the flexible closure and the speaking diaphragm being independent of the aforesaid stationary cup; and a spring structure for pressing said medium into engagement with the speaking diaphragm where it engages the same.

7. A telephone transmitter including a stationary cup having a flexible closure; transmitter electrodes presented to the interior of the cup, one of these electrodes being carried by the flexible closure so as to be movable; comminuted current conducting material within the cup and interposed between the electrodes for electrically connecting the same in the transmitter circuit; a speaking diaphragm; and a substantially rigid medium for conducting vibrations interposed between the electrode carried by the flexible closure and a portion of the speaking diaphragm laterally disposed with respect to said electrode, such interposition of said medium between the electrode carried by the flexible closure and the speaking diaphragm being independent of the aforesaid stationary cup; and a spring structure for pressing said medium into engagement with the speaking diaphragm where it engages the same.

In witness whereof, I hereunto subscribe my name this 9th day of August A. D., 1911.

ROSCOE ROYAL.
